TRENCH WARFARE DEVICE

Filed April 5, 1923

2 Sheets-Sheet 2

UNITED STATES PATENT OFFICE.

CHARLES E. SPARHAWK, OF DRUMBELLER, ALBERTA, CANADA.

TRENCH-WARFARE DEVICE.

Application filed April 5, 1923. Serial No. 630,176.

To all whom it may concern:

Be it known that I, CHARLES E. SPARHAWK, a subject of the King of Great Britain, residing at Drumbeller, in the Province 5 of Alberta, Dominion of Canada, have invented certain new and useful Improvements in Trench-Warfare Devices, of which the following is a specification.

This invention relates to a combined 10 protector and elevator for gunners.

In trench warfare it is desirable to elevate a gunner above the trench and in such a position that he may command a view of the lines of the enemy providing this can 15 be done without too great a hazard or danger to the gunner.

With this in view it is the general object 20 of the present invention to provide a protector or housing adapted to accommodate a gunner together with a machine gun or like destructive implement and also provide means for elevating the housing or protector, said means being adapted to be positioned in a trench or like excavation.

It is also an important object of the 25 invention that the device or apparatus be of a knock-down structure and portable.

A further object of the invention is that 30 means be provided whereby the housing or protector may be rotated by the gunner or other person therein and thereby to permit the gunner to accurately direct the projectiles which he may fire from the housing.

A still further object of the invention is 35 that the housing or protector be easily and quickly lowered and that the gunner or other person in the housing may lower the same at will.

It is a still further object of the invention 40 that means be provided whereby the housing or protector may be tilted longitudinally and in either direction and thereby to further aid the gunner in directing his fire toward the enemy.

Other objects, and objects relating to 45 details of construction, combination and arrangement of parts, will hereinafter appear in the detailed description to follow.

The invention is illustrated by way of 50 example in the accompanying drawings, in which:—

Figure 1 is a perspective view illustrating 55 the arrangement of a plurality of devices of the present invention when employed in trench warfare,

Figure 2 is a view in side elevation of the device when positioned in a trench and also showing the housing or protector elevated.

Figure 3 is a vertical sectional view of the device illustrated in Figure 2, the section 60 being taken longitudinally and centrally of the housing,

Figure 4 is a horizontal sectional view taken on the line 4—4 of Figure 3 when looking upward,

Figure 5 is a sectional view taken substantially on the line 5—5 of Figure 2 and when looking in the direction of the arrows.

Like reference numerals designate corresponding parts throughout the several views 70 of the drawings.

Referring to the drawings in detail, 10 indicates generally a base which may be plate-like in formation as shown and which is preferably supported by a plurality of 75 rollers 11. The base is formed with an upstanding cylinder 12, the upper end of which is provided with a closure 13 having formed therein a plurality of ports 14. Upon the cylinder 12 there may be secured adjacent the lower end thereof a pair of pump cylinders 15, each of which is provided with a suitable piston or plunger and connected to the handle 16, as at 17, said handle 16 being pivotally supported, as at 18, by suitable 80 bracket arms 19. Each cylinder 15 may communicate with the atmosphere and also with the interior of the cylinder 12 through one-way valves of any conventional construction. Adjacent the bottom or lower 85 end of the cylinder 12 there is provided an outlet valve 20 which may be operated through a bell-crank lever 21. The purpose of this valve will later become apparent.

Upon the exterior surface of the cylinder 90 12 there is provided a plurality of ribs which are arranged in pairs, as indicated at 22 and 23. Each pair of ribs may be provided with registering openings 24 adapted to receive in each instance a pin or bolt 25, 100 whereby to pivot the one end of a brace-rod 26. Each rod 26 telescopically receives a tubular member 27 at its outer end and a suitable lock lever 28 is carried by each tubular member 27, whereby the same may 105 be adjustably held upon the associated rod 26. Each tubular member 27 terminates at its outer end in a circular head 28, said head having formed upon its front face a spike or tooth 29.

Within the cylinder 12 there is slidably a piston head 30, said piston head being provided with suitable packing rings as shown and being rigidly connected to a post 32, said post being slidable through a suitable opening in the upper end closure 13 of the cylinder 12 carrying at its upper end a head member 33. The head member 33 is formed upon its lower end with a lug 34 and the upper end of the post 32 is bifurcated to provide prongs or projections between which the lug 34 may be received. The lug 34 is pivotally supported by the post 32 through the means of a bolt 35 and said bolt may carry a lock nut 36, whereby the head 33 may be adjustably locked in an adjusted position with relation to the post 32. The head 33 is formed with a central and vertical bore 37 which is adapted to receive a stub shaft or spindle 38. The spindle 38 is formed adjacent its lower end with an annular groove 39. The head 33 is provided with a boss 40 which is provided with a bore 41 adapted to receive the head 42 of the pin 43, said pin projecting through a reduced inner end portion of the bore 41 and its free end being disposed within the annular groove 39 of the spindle 38. A coil spring 44 is adapted to press the pin 43 inwardly, and this coil spring is held in position by a screw plug 45. Also the coil spring 44 is preferably secured to the pin 43 so that the same may be utilized in withdrawing the pin from the groove 39.

The housing or protector, generally indicated by the reference numeral 46, may comprise a middle section 47, a rear end section 48 and a forward section 49. The sections 47 and 48 are preferably cylindrical in shape and threadedly connected to each other, as at 50. The section 49 tapers toward its forward end and is threadedly connected to section 47, as at 51. The section 49 may have a small opening 52 in its forward end, the purpose of which will later be described.

The housing section 47 is formed with an exterior boss 53 which is provided with a bore centrally thereof, and said bore communicating with the interior of the housing section 47. The spindle 38 is positioned in the bore of the boss 53 and the upper end portion 54 of the spindle is squared as shown in Figure 3. Also the spindle 38 terminates at its upper end in a squared head 55 and the bore of the stud 53 is adapted to seat this head and in this way rigidly secure the housing to the spindle 38. Between the boss 53 and the upper end of the head member 33 there is interposed ball bearings 56 and thereby to facilitate the turning movement of the housing 46. The boss 53 of the housing section 47 is formed with sprocket teeth 58, over which there is trained a sprocket chain 59, said sprocket chain being also trained over a sprocket wheel 60 rotatably

supported by a section 49. The sprocket wheel 60 may have ball bearings 61 associated therewith to facilitate turning movement thereof and within the section 49 there is provided a crank 62 whereby the sprocket 60 and wheel 61 may be rotated by the gunner or other person within the housing 46, and in this way revolve the housing 46.

Within the housing 46 there may be positioned a machine gun, generally indicated by the reference numeral 63, which may be supported by the usual tripod 64. The barrel of this machine gun may extend through the opening 52 of the housing section 49 and the opening 52 should be sufficiently large to permit a gunner 65 to see the sights of the machine gun and also to see the enemy.

Also it should be noted that the section 47 of the housing is provided with an opening 67 through which the gunner may speak to those below. Furthermore, a cable 68 may have its one end connected to the tripod 64 or other suitable means within the housing 46 and its other end connected to the bell-crank lever 21, as illustrated to advantage in Figure 2, whereby to provide means by which the gunner or person within the housing 46 may open the lower end of the cylinder 12 and permit the housing to descend.

Referring to Figure 1, 68 indicates a trench and 69 indicates a plurality of passages leading to this trench. As shown in this figure a number of these devices are arranged in the trench 68 and the housing 46 of each device has been elevated so that the gunner therein is brought to a level for firing at the enemy disclosed at a distance forward to the trench 68.

In utilizing the present device the same may be in a disassembled state, that is, the housing 46 may be knocked down or disassembled, the post 32 lowered and the brace members 27 moved inward upon the brace rods 26 and folded upon the cylinder 12.

The sections of the housing may be braced in any suitable manner upon the platform or base 10, and if desired one or more persons may draw the device when in this condition to a trench and bring the same to a desired position in said trench. The housing 46 may then be assembled and placed upon the head 33, that is, the spindle 38 may be positioned in this head 33 and then the pin 43 brought to its locking position.

The brace members 47 may now be moved outwardly upon the rods 26 and brought to engage the side walls of the trench as illustrated to advantage in Figures 2 and 3. These members may be adjusted as shown in dotted lines in Figure 2 so that the greatest bracing action therefrom for the device may be had. The gunner may take his position within the housing 46 and then one or more persons may operate the air pumps carried

by the cylinder 12 and heretofore described, whereby to supply sufficient compressed air to raise the housing to the position desired. As shown in the drawings the housing should be raised to such position that the barrel of the gun 63 will project above the trench wall. When the gunner is in this position he may utilize the crank member 62 for revolving the housing in order to bring his gun in the proper position. Also as heretofore stated the opening 52 may permit a slight up and down motion of the gun 63 and therefore to aid the gunner in firing upon the enemy. Should the gunner wish to have the housing tilted in either direction with respect to its length he may inform those below by speaking through the opening 67 and those informed may loosen the nut 36 and tilt the housing the desired degree and in the desired direction. It might be here stated that with the gunner in the position shown in Figure 3, the housing is substantially balanced and, therefore, the housing could be adjustably tilted in an easy manner. Also it might be mentioned that in case the gunner needs ammunition the same may be passed upwardly through the opening 67 of the housing section 47. In case that the gunner wishes to quickly descend then he need only draw upwardly on the rope 68, whereby to open the valve 20 and thus relieve the pressure beneath the piston 30 and permit the housing 46 to descend.

It should be further mentioned that with a device of this character the housing 46 is better adapted to accommodate a gunner of relatively small stature and in this way to provide means whereby small persons may be efficiently employed in trench warfare. It should also be observed that while I have shown my device employed in connection with trench warfare it is apparent that the same may be placed in any excavation which would not represent a trench and utilized with equal advantages.

It should be pointed out that the device can be easily and quickly disassembled and thus in case of a "barrage" of the enemy the present device could be taken down and moved to some safer place in the trench or moved into a "dug-out." Furthermore, the protector or housing should be made of material which would resist the impact of projectiles from small gun fire.

Also in order to further brace the device guy wires or cables 70 may be employed.

While I have shown and described the preferred form of my invention, I wish it to be understood that I am aware of the fact that the construction, combination and arrangement of parts may be changed by those skilled in the art without departing from the spirit of the invention as indicated by the appended claims.

I claim:

1. In combination, a running gear adapted to be positioned in a trench or excavation, an elongated housing supported by said running gear, said housing being adapted to accommodate a person and having an opening in its one end through which projectiles may be fired by said person, means for elevating said housing with respect to the running gear, and means whereby said housing may be tilted in either direction with respect to its length. 70

2. In a trench warfare device, a horizontally elongated housing having its forward end provided with an opening through which projectiles may be fired, said housing being adapted to accommodate a person in a reclining position and having its rear end open to facilitate entry into and exit from said housing, supporting means for said housing, said supporting means including elements adjustable vertically relative to each other so that the elevation of the housing may be varied, a connection between the housing and the supporting means, said connection having a part fixed to the housing and a part tiltably secured to one of the elements of the supporting means, the parts of the connection being rotatably secured to each other, and manually operable means controllable by the person within the housing and effective to rotate the housing relative to the supporting means. 85 90

3. In a trench warfare device, a horizontally elongated housing having an end provided with an opening through which projectiles may be fired, said housing being adapted to accommodate a person in a reclining position, supporting means for said housing, said supporting means including elements adjustable vertically relative to each other so that the elevation of the housing may be varied, a connection between the housing and the supporting means, said connection having a part fixed to the housing and a part secured to one of the elements of the supporting means, the parts of the connection being rotatably secured to each other, and manually operable means controllable by the person within the housing and effective to rotate the housing relative to the supporting means. 105 110 115

4. In a trench warfare device, a housing provided with an opening through which projectiles may be fired, said housing being adapted to accommodate a person in a reclining position, supporting means for the housing including a vertical cylinder arranged in the trench, a piston in said cylinder, air pumps operable from within the trench and connected with the cylinder whereby the piston may be elevated within the cylinder to the desired degree, a post connected to the piston and upstanding from 125 130

the cylinder, said post being connected to the housing, an outlet valve connected with the lower end of the vertical cylinder, and means for controlling said outlet valve from the interior of the housing.

5. In a trench warfare device, a housing provided with an opening through which projectiles may be fired, said housing being adapted to accommodate a person in a reclining position, supporting means for the housing including a vertical cylinder arranged in the trench, a piston in said cylinder, air pumps operable from within the

trench and connected with the cylinder whereby the piston may be elevated within 15 the cylinder to the desired degree, a post connected to the piston and upstanding from the cylinder, a connection between the post and the housing including a part fixed to the housing and a part connected to the post, said parts being relatively rotatable with respect to each other and manually operable means controllable by the person in the housing and effective to rotate the housing relative to the supporting means.

CHARLES E. SPARHAWK.
